UNITED STATES PATENT OFFICE.

PEARL E. MILLER, OF NESCOPECK, PENNSYLVANIA.

HATBOX.

Application filed March 9, 1923. Serial No. 623,979.

To all whom it may concern:

Be it known that I, PEARL E. MILLER, a citizen of the United States, residing at Nescopeck, in the county of Luzerne and State of Pennsylvania, have invented certain new and useful Improvements in Hatboxes, of which the following is a specification.

This invention relates to a novel improvement in hat boxes.

A primary object is to provide a collapsible hat box which when set up will be firm and which when collapsed will occupy but little space. Thus when travelling on trains, the user may protect her hat by setting up the box and positioning her hat therein, and when it is undesirable to use the box it may be collapsed and packed in her suitcase.

Another object of my invention lies in providing a hat box of such a construction as will permit freedom of movement when inserting or removing a hat.

A further object is to provide a hat box having a hat-supporting means to prevent the weight of the hat being carried by the hat brim, the hat-supporting means being of such a character that it will not interfere with the collapsing of the box.

A still further object is to provide a hanger for the box whereby the latter may be attached to the back of a car seat or other support.

In the accompanying drawings which illustrate one form of my invention:

Figure 1 is a perspective view of my improved hat box.

Figure 2 is a vertical sectional view thereof,

Figure 3 is a plan view of the box in its collapsed position,

Figure 4 is a perspective view of the hook supporting stay, and

Figure 5 is a perspective view of the hook.

As previously indicated, it is the purpose of the present invention to provide a convenient way of carrying a hat, for example, a lady's hat when traveling, and to also provide a container which may be readily used in department stores or the like, and in which latter case would afford an attractive hat case which could conveniently bear the advertisement of the store, thus providing a device which has combined utility and advertising value.

Referring to the drawings, my improved

collapsible hat box is formed from fiberoid, or other relatively stiff fibrous material and is preferably formed from a single blank to provide a front wall 5, a rear wall 6, side walls 7—7 hingedly connected to said front and rear walls, bottom end flaps 8—8 hingedly connected to the side walls, a bottom closure 9 hingedly connected to the front wall 5 and having a closure flap 10, top end flaps 11—11 hingedly connected to the side walls, and a top closure 12 hingedly connected to the rear wall 6 and having a closure flap 13, one side wall being permanently connected to the rear wall 6 by a flap 7^a by cement or the like.

In setting up the box, the bottom end flaps 8—8 are first infolded and the bottom closure 9 folded thereover, the bottom closure flap 10 being inserted between the rear wall 6 and the bottom end flaps 8. The rear wall 6 and the bottom closure flap 10 are respectively formed with openings 6^a and 10^a which will be brought into alinement when the parts are set up as above described. A detachable fastener 14 is inserted through these openings and serves to retain the bottom in its set-up position.

The upper portion of the front wall 5 is cut away as at 15 to provide an opening of sufficient size to give freedom of movement to a hat while the latter is being inserted in the box or while being removed therefrom. The top closure flap 13 is adapted to extend below the cut-away portion 15, and is formed adjacent the lower edge with an opening 16 which is reinforced with a sheet metal stay 17, the opening being adapted to receiving the hasp 18 which is secured to the front wall 5, thus providing means for detachably locking the top closure 12 and flap 13 thereof against accidental opening.

In order to carry the box when set up I have provided a handle 19, the end portions thereof having interlocking engagements 100 with straps 20—20 integrally formed in the top closure 12 by slitting the latter.

It is desirable to provide means for supporting a hat within the box when the latter is set up whereby the weight of the hat will not be carried by the brim. To this end I have provided an elongated sheet metal stay 21 which lies against the upper central portion of the inner face of the rear wall 6 and is secured thereto by upper and lower fasteners 22 and 23, the longitudinal axis of the stay being disposed in a vertical plane.

This stay is stamped to provide a plurality of spaced bearings 24 arranged in vertical alignment, and the bearings below the upper one are each formed at its upper edge with a centrally disposed notch 25. A hook 26 for supporting the hat is formed from a piece of spring wire, the wire being rebent to form spaced upper and lower legs 27 and 28 which respectively terminate in upwardly and downwardly extending attaching feet 29 and 30. The feet are respectively positioned in an adjacent pair of bearings 24-24, the notch 25 of the lower bearing receiving the lower leg 28 of the hook to form a detachable interlocking engagement therewith and thereby retain the hook in a plane at right angles to the plane of the rear wall. The hook is located at a point opposite the cut away portion 15 of the front wall and as a result easy access may be had to the hook when it is desired to adjust the vertical position thereof to conform to the size of a given hat, or when it is desired to swing the hook into parallelism with the rear wall so as not to interfere with the proper collapsing of the box.

In order to provide means for attaching the box to the back of a car-seat or other support, I have provided a sheet metal hanger 31 which is positioned against the rear face of the rear wall and is pivotally secured not only to the rear wall but also to the stay 21 by the upper fastener 22. The hanger is of a length sufficient to project above the top closure and the upper or free end thereof is formed with an opening 32 through which a pin may be passed for supporting the box. When the hanger is not in use it may be swung downwardly to

the position shown in Figure 3. By connecting the hanger and stay together by the fastener 22 I avoid any tendency of the weight of the box and hat from tearing the rear wall or otherwise injuring the hanger connection.

From the foregoing the advantages of the improvements will be readily apparent, and it will be understood that changes in the form, proportion and minor details may be made without departing from the spirit of the invention.

I claim:

1. A hat box comprising a collapsible body adapted to be opened from its flat condition to form a cubical receptacle, a metal stay fixed to the inside rear wall of the receptacle, a hat supporting hook connected to said stay, a hanger on the outside of said wall and also secured to said stay through the back wall of the receptacle.

2. A hat box comprising a collapsible body formed of relatively stiff paper scored along lines to produce folds whereby the body may be opened from its flat condition to form a cubical receptacle, a hat support carried by the inner rear wall of the body and the front wall of the body opposite the hat support being cut away to provide hat clearance, and the upper wall of said body being provided with a flap to cover said cut way portion, and a carrying handle fitted to said top wall.

In testimony whereof I hereunto affix my signature in the presence of two witnesses.

PEARL E. MILLER.
